WIRELESS RECEIVING APPARATUS

James Robinson, London, England, assignor, by
mesne assignments, to British Radiostat Cor-
poration, Limited, a corporation of Canada

Application March 3, 1931, Serial No. 519,810, and
in Great Britain March 6, 1930

5 Claims. (Cl. 250—20)

This invention is for improvements in or relating to wireless and like receiving apparatus and is concerned with receivers of the type having very high selectivity and/or low damping and employing for this purpose a resonant device such as a piezo-electric crystal, or a tuning fork, or a thermionic valve system with retroaction, or a plurality of tuned circuits in cascade or other filter systems. Examples of such highly 5 selective receivers are described in my prior United States Patents Nos. 1,821,032 and 1,821,033, granted September 1, 1931.

With such receivers it is possible to separate and receive independently any of a plurality of 15 transmissions located closer together than is permissible for satisfactory reception with normal receivers, but in some circumstances a very small amount of interference energy may be received and produce heterodyne beat effects with the 20 transmission it is desired to receive. An object of the present invention is to provide means for suppressing such interference.

Owing to the high selectivity and/or low damping of the receivers with which this invention 25 is concerned the percentage of modulation of the received signals is very much reduced both in the case of the signals to which the receiver may be tuned and also of interfering signals not in resonance with the receiver. The interfering 30 signals are, however, received at a very small volume owing to the high selectivity and since the percentage modulation is decreased, little or no modulation effects of the interference are produced. The interference can, therefore, for 35 all ordinary purposes be obviated by suppressing the basic frequency of the interference or the heterodyne beat note it produces with the basic frequency of the desired signals.

The invention therefore comprises a wireless 40 or like receiver in which there is provided a highly selective and/or low damped resonator such that an interfering modulated transmission is reduced therein to a substantially non-modulated form, in combination with means (e. g. one or more 45 filters or the like) for suppressing this interference or the heterodyne beat effect produced thereby.

Owing to the persistence of the signals in 50 these highly selective and/or low damped receivers, a distortion of the signals occurs and usually means will be provided for the correction of this distortion for example as described in my prior patents hereinbefore mentioned.

In one form the means for suppressing the 55 heterodyne effect comprises a filter (e. g. a me-

chanical resonator) sharply tuned to the heterodyne beat note and by-passing the electrical effects thereof. By this means a heterodyne note which is within the range of modulation signals being received may be suppressed. In 60 another form for suppressing heterodyne beat notes higher in frequency than the highest modulation signal required for reproduction, there is provided a low-pass filter for the modulation signal frequencies. Also instead of or in 65 addition to the aforesaid low-pass filter for modulation signal frequencies there may be provided a band-pass filter for stopping all frequencies differing from the carrier or basic frequency of the signals (or a conversion of this 70 frequency) by an amount equal to the frequency of the highest modulation signal required for reproduction, this band-pass filter having a sharp cut-off for the band and comprising, for example, a high-pass filter and a low-pass filter. 75

Several examples of receivers according to the invention are hereinafter described with reference to the accompanying drawing indicating such receivers in a purely diagrammatic manner and in which:—

Figure 1 is a general diagram of a highly selective receiver employing a sharply tuned filter for suppressing a heterodyne beat note;

Figure 2 indicates a receiver employing a low-pass filter for modulation signals;

Figure 3 a receiver employing high- and low-pass filters and;

Figure 4 indicates a receiver having a sharply-tuned filter for suppressing a specific interference, together with a low-pass filter for modulation 90 signals.

Referring to Figure 1 there is indicated at 10 a highly selective receiving apparatus, for example, a receiver such as is described in my prior patents hereinbefore identified. The receiver comprises 95 in addition to the normal tuning and amplifying devices a highly selective device such as a piezo-electric crystal, a tuning fork resonator or very low damped tuned circuits such that when arranged for the reception of a given transmission 100 an interfering transmission close to the desired transmission in regard to the basic frequencies (for example, 2 kilocycles apart) produces only a very small and substantially unmodulated effect as hereinbefore described. The heterodyne beat 105 note produced will thus be present at the output terminals 11 of the receiving apparatus 10 and in the example indicated this note will have the frequency of 2000 cycles.

According to the invention there is provided 110

a sharply tuned filter for by-passing this beat note and in the example shown there is provided a tuning fork 12 and co-operating electro-magnets 13 connected respectively in series between 5 the terminals 11 and final output terminals 14 of the receiver.

The arrangement is similar to that shown and described in my prior patent application Serial No. 514,599, filed February 9, 1931. It will be 10 understood that one of the coils 13, when fed with energy at a frequency corresponding to the mechanical resonant frequency of the tuning fork, serves to set the fork in vibration at that frequency, and the motion of the fork produces 15 electrical variations in the other of the coils 13 at the frequency in question.

It will thus be observed that energy at the resonant frequency of the tuning fork is transmitted from one to the other of the coils 13 and thus 20 the tuning fork provides a low impedance path for the electrical frequency corresponding to its own mechanical resonant frequency but is not appreciably affected by other electrical frequencies. This tuning fork filter is arranged in parallel 25 with the output terminals 14 of the apparatus, and since the tuning fork is arranged to have a resonant frequency that is the same as the frequency of the heterodyne note it is desired to eliminate the corresponding electrical effects are 30 by-passed by the tuning fork and do not appear in the loud-speaker or other instrument which may be connected to the output terminals 14. If desired two or more heterodyne effects may be eliminated in like manner by using corresponding 35 tuning forks and moreover sharply tuned devices other than tuning forks may be employed if desired. Also, mechanically operative means, or an acoustic filter may be employed to prevent the reproduction of the heterodyne note in a signal 40 reproducing device such as a loud-speaker.

According to present conditions it is usually accepted that for telephony and music signal frequencies above about 5000 cycles are not necessary for satisfactory reproduction.

45 In these circumstances it is possible to suppress all heterodyne and other interferences at audio frequencies higher than 5000 cycles or whatever other limit is required by employing instead of a sharply tuned filter to eliminate only one 50 audio frequency, as described with reference to Figure 1, a filter which has a sharp cut-off in the neighborhood of 5000 cycles for suppressing all 55 higher frequencies. In Figure 2 there is indicated at 10 a receiving apparatus which is highly selective, as hereinbefore described, such that in separating stations closely adjacent as regards frequencies, the interfering transmission is reduced to substantially unmodulated form. Thus, for example, an interfering transmission spaced from 60 the wanted transmission by 6000 cycles and having side-bands which overlap the side-bands of the wanted signals produces substantially no interference with the exception of the beat-note between the carrier waves of the interfering and 65 wanted transmissions. To the output of the highly selective receiver 10 there is connected a low-pass filter indicated at 15. This low-pass filter, which may be of usual construction comprising 70 series connected inductances and shunt connected condensers, is designed to pass the signal frequencies below, say, 5000 cycles and stop all heterodyne and other signal effects of higher frequencies. Thus, by means of this low-pass filter 75 the heterodyne beat-note of 6000 cycles as given in the example referred to above is suppressed.

The combination of the very highly selective receiver and the low-pass filter for audio frequencies consequently provides reception with substantial freedom from interference of unwanted transmissions removed from the carrier wave of the wanted transmission by more than 5000 cycles or other limit which may be required in any particular case.

It will be understood that instead of employing a low-pass filter for audio signal frequencies as described with reference to Figure 2 or, if desired, in addition thereto, a band-pass filter may be employed for the high frequency signals that are applied to the receiver or to frequency conversions of these signals. Thus, as indicated 80 in Figure 3, the received signals are first applied to a high-pass filter 16 and then through a low-pass filter 17 arranged to pass signal energy only of those frequencies within a band extending, for example, 5000 cycles above and below the basic or carrier frequency of the wanted transmission. The output from the filter 17 is applied to the highly selective receiving apparatus indicated at 10. It will be appreciated that this arrangement of high and low-pass filters is very 90 similar in effect to the arrangement described with reference to Figure 2 employing an audio frequency filter having a sharp cut-off in the neighborhood of 5000 cycles. Thus, by means of the high and low-pass filters no signal energy of 100 frequencies more than 5000 cycles from the frequency of the carrier wave of the wanted transmission is permitted to be passed on in the receiver with the consequence that no heterodyne beat 110 effects (involving the wanted carrier) of frequencies higher than 5000 cycles are produced.

As above indicated, instead of employing a filter such as described with reference to Figure 1 for suppressing the heterodyne beat-note produced by the carrier wave of an unwanted transmission beating with the carrier wave of the wanted transmission, the carrier wave of the unwanted transmission may itself be suppressed by means of the filter which is sharply tuned to this 115 frequency. Such an arrangement is incorporated 120 in the receiving apparatus diagrammatically shown in Figure 4. In this apparatus, which is of the superheterodyne type, there is shown a detector valve 20 which is connected to a frame aerial 21 and to a local oscillator 22 in known manner. The detector valve is connected to an intermediate constant-frequency amplifier generally indicated at 23 comprising in this instance a plurality of tuned circuits coupled in cascade. The output of the intermediate frequency amplifier is connected to a second detector valve 24 and the resulting audio frequency signals are 130 passed through a correcting device 25 to the output valve 26. The intermediate frequency amplifier 23 provides a very high degree of selectivity with the result that the audio-frequency signals are distorted, the higher notes being diminished with respect to the low notes. This distortion is compensated for by the correcting device 25 which 135 has a rising amplitude frequency characteristic for this purpose. This receiver thus far described is of the kind concerned in my prior patents hereinbefore identified. With this receiver the interference produced by an unwanted transmission 140 closely adjacent as regards frequency to the wanted transmission to be received is reduced as hereinbefore described to substantially unmodulated form, and the interference which is obtained is thus mainly the remaining effect of the 145 150

beat-note between the carrier waves of the unwanted and wanted transmissions.

Assuming that it is required to receive all modulation frequencies up to 5000 cycles, which is according to present practice, and the carrier wave of the interfering transmission is spaced from the carrier wave of the wanted transmission by less than 5000 cycles, there is inserted in the intermediate frequency amplifier 23 a highly selective filter to suppress the carrier wave of the unwanted transmission. As shown in the final tuned circuit of the intermediate frequency circuit amplifier 23, there is provided a piezo electric crystal 27 having a resonant frequency equal to the interfering carrier wave as converted in this instance by the oscillator 22. By suppressing this interfering carrier wave, therefore, no heterodyne beat-note is produced, and consequently no interference appears in the final output of the receiver.

In order to prevent interference by heterodyne beat-notes resulting from the wanted carrier wave beating with interfering carrier waves more than 5000 cycles removed, there is provided a low-pass filter indicated at 28 which is designed to pass all audio signal frequencies below, say, 5000 cycles and suppress all heterodyne and other audio effects of higher frequencies, as more specifically described above with reference to Figure 2.

Thus, in the arrangement shown in Figure 4 the heterodyne beat-notes produced by combination of the wanted and unwanted carrier waves and appearing either in the required audio frequency range or outside of that range are suppressed, thus providing highly disturbance-free reception.

Owing to the very high selectivity of the receiving apparatus distortion may be introduced and means may be employed, for example, as described in my prior Patents Nos. 1,821,032 and 1,821,033 for the correction of this distortion; such correction means may be included in the receiving apparatus indicated at 10.

In an embodiment as shown in Figure 2 of the drawing the low-pass filter thereof may be combined with the distortion-correcting means in the receiver.

I claim:

1. In apparatus for receiving a carrier wave modulated by a range of wanted signal frequencies, the combination of a resonant device having such high selectivity that interfering modulated carrier wave signals, whereof the carrier wave differs from the carrier wave of the wanted signals by an amount less than the highest modulation frequency of the wanted signals, are reduced to substantially non-modulated form and an output circuit for said resonant device including a filter for suppressing the interference of the remaining substantially non-modulated carrier-wave.

2. In apparatus for receiving a carrier wave

modulated by a range of wanted modulation signal frequencies, the combination of a resonant device having such high selectivity that interfering modulated carrier wave signals, whereof the carrier wave differs from the carrier wave of the wanted signals by an amount less than the highest modulation frequency of the wanted signals, are reduced to substantially non-modulated form, the remaining carrier wave of the interfering signals heterodyning with the carrier wave of the wanted signals and an output circuit for said resonant device including a modulation frequency filter for suppressing the resulting heterodyne beat-note.

3. In apparatus for receiving a carrier wave modulated by a range of wanted signal frequencies, the combination of a resonant device having such high selectivity that interfering modulated carrier wave signals, whereof the carrier wave differs from the carrier wave of the wanted signals by an amount less than the highest modulation frequency of the wanted signals, are reduced to substantially non-modulated form, the remaining carrier wave of the interfering signals heterodyning with the carrier wave of the wanted signals, and an output circuit for said resonant device including a sharply tuned mechanically resonant filter for modulation signal frequencies to suppress the resulting heterodyne beat-note.

4. In apparatus for receiving a carrier wave modulated by a range of wanted signal frequencies, the combination of a resonant device having such high selectivity that interfering modulated carrier wave signals, whereof the carrier wave differs from the carrier wave of the wanted signals by an amount less than the highest modulation frequency of the wanted signals, are reduced to substantially non-modulated form, an output circuit for said resonant device including a filter for suppressing the remaining carrier wave of said interference and a modulation frequency filter for suppressing modulation signal frequencies of a higher order than the highest modulation signal required for reproduction.

5. In apparatus for receiving a carrier wave modulated by a range of wanted signal frequencies, the combination of a resonant device having such high selectivity that interfering modulated carrier wave signals whereof the carrier wave differs from the carrier wave of the wanted signals by an amount less than the highest modulation frequency of the wanted signals, are reduced to substantially non-modulated form, a filter for suppressing the interference of the remaining substantially non-modulated carrier wave, and an additional filter for suppressing modulation signal frequencies of a higher order than the highest modulation signals required for reproduction.

JAMES ROBINSON.
